FOLDING TABLE LEG STRUCTURE WITH
SPRING LATCHCharles T. De Puy, Brighton, N. Y., assignor to
Trimble, Inc., Rochester, N. Y., a corporation
of New York

Application August 13, 1953, Serial No. 373,985

4 Claims. (Cl. 311—87)

1

This invention relates to a folding table or stand for serving purposes, and has for its purpose to afford a structure including two inverted U-shaped leg frames which are collapsible against the bottom of the table body in a ready and convenient manner, and which support the table firmly when in operative position.

A further purpose of the invention is to afford a simple structure employing two inverted U-shaped leg frames that can be economically manufactured and in which the leg frames can be compactly folded against the table body when the latter is to be packed or stored.

Still a further object of the invention is to afford improved means for supporting and securely locking inverted U-shaped leg frames in operative position against accidental displacement, so that they can be readily released and moved from operative to inoperative position when the table is to be folded.

Still an additional object of the invention is to afford simple and effective locking means for holding the upper portions of the inverted U-shaped leg frames in operative position, and which can be easily released to permit folding the leg frames.

To these and other ends, the invention consists in the construction and arrangement of parts that will appear clearly from the following description when read in conjunction with the accompanying drawings, the novel features being pointed out in the claims following the specification.

In the drawings:

Fig. 1 is a view in side elevation of a table incorporating a preferred embodiment of the invention, the leg frames appearing in full lines in operative or unfolded position, and showing in dotted lines the position which a leg frame assumes in moving to folded position;

Fig. 2 is a bottom plan view showing the leg frames folded;

Fig. 3 is a view in end elevation looking from right to left of Fig. 1;

Fig. 4 is an enlarged detail sectional view on line 4—4 of Fig. 2;

Fig. 5 is an enlarged detail sectional view on line 5—5 of Fig. 2;

Fig. 6 is an enlarged detail sectional view taken on line 5—5 of Fig. 2, showing the leg frame in operative position as in Fig. 1, and

Fig. 7 is a detail perspective view, partially broken away, showing one channel strip for receiving a leg frame and its locking means.

Referring more particularly to the drawings

in which like reference numerals refer to the same parts throughout the several views, the invention is illustrated in a preferred embodiment as applied to a rectangular table or body indicated at 1 formed preferably of metal such as aluminum and provided with a stamped curved rim 2 defining its outer edge, and pivotally supported on the underside of the table are two leg frames of inverted U-shape which can be folded adjacent to the bottom of the table and when thus folded are housed lengthwise of the table adjacent to said curved rim in juxtaposition to each other, and which when in operating position extend downwardly beneath the table from a point spaced from the ends thereof to a point approximately in vertical alignment with the ends of the table so as to support the latter firmly and solidly.

To accomplish this, there are attached to the bottom of the table 1 metal angle strips each including a base portion 3 extending endwise of the table in spaced relation to the rim 2 and attached to the bottom by rivets 4, the angle strips including depending portions or flanges 5 extending endwise of the tray and to which links 6 are pivotally attached at 7, the outer ends of the links being pivotally connected at 8 to the legs 9 of the leg frames which are of inverted U-shape, and so related that when in operative position, the upper portions of the leg frames rest against the bottom of the table while the legs occupy vertically inclined positions with relation to the table, as illustrated in Figs. 1 and 6.

When in folded or inoperative position, the leg frames occupy the positions illustrated in Fig. 2, being then located in juxtaposition within the rim 2 of the table with the top portions 11 of the leg frames arranged at the ends of the table and the legs 9 arranged at the sides of the table between the flanges 5 and the outer portions of rims 2, see Fig. 4, the leg frames both occupying the same horizontal plane with the ends of the legs in juxtaposition, as shown in Fig. 2. The legs are moved from the folded position illustrated in Fig. 2 to the operative position shown in Fig. 1 by first drawing the legs away from the table, as illustrated in dotted lines in Fig. 1, until the top portions 11 of the leg frames are spaced from the table, and the leg frames can then be swung on the supporting pivots 8 of links 6 and the links 6 swung on their supporting pivots 7 until the leg frames are in the full-line position illustrated in Fig. 1, to support the table on a floor or other surface.

In order to retain the leg frames in operative

position, transversely arranged strips are provided affording channels, these including base portions 12 which overlie the base portions 3 of the angle strips and are riveted thereto and to the bottom of the tray at 13, see Fig. 2, said strips including transversely extending depending inner flanges 14 and transversely extending depending outer flanges 15 spaced from the inner flanges 14 and of less height than the inner flanges 14 in order to permit ready clearance of the leg frame when moving from one position to the other, while the greater height of the inner flange 14 affords a lateral brace for the top portion 11 of the leg frame when the latter is in operative position, as shown in Figs. 1 and 6.

In order to retain the leg frames in operative position with their top portions 11 supported and retained against the inner flanges 14 of the channel strips, there is provided a spring locking means or catch for each channel strip, consisting of a spring-plate 16 riveted at 17 to the inner depending flange 14 and having a laterally extending tongue 18 projecting through an opening 19 in the flange 14 and engageable in an opening 21 provided in the upper portion 11 of the U-shaped leg frame. The leg frames are preferably of tubular stock of cylindrical cross-section so that when an upper portion 11 is moved inwardly toward the table and pushed into the channel formed between the flanges 14 and 15, see Fig. 6, the locking tongue 18 is forced outwardly by the engagement of the outer curved surface of the top portion 11 of the leg frame with the curved end 22 of the tongue 18 until the opening 21 in the leg frame is in position to receive the locking tongue 18 which thereupon springs into the opening 21 and holds the leg frame securely in operative position with the upper portion of the leg frame supported against the inner flange 14 of the channel and thereby retained against lateral movement, while the angular or inclined disposition of legs 9, see Fig. 1, in relation to the table tends to retain the upper portions of the leg frames against the inner depending flanges 14 of the channels and in the channel when weight is supported on the table. To release the leg frames, it is only necessary to engage the free end 23 of each locking plate 16 and pull the locking plate away from the upper portion 11 of the leg frame sufficiently so that the tongue 18 clears the opening 21 in the leg frame, which can then be moved away from the table in the manner illustrated in dotted lines in Fig. 1 and swung inwardly to its folded position.

When the leg frames are folded, the links 6 occupy positions between the longitudinally extending flanges 5 and the legs 9, see Fig. 4, and when thus folded, the parts are compactly arranged with the legs and leg frames occupying a minimum space and housed entirely within the longitudinal confines of the table.

The structure affords a table with foldable legs of inverted U-shape which enable supporting the table at maximum height for the size of the leg frames, holding the table firmly and the leg frames in rigid relation thereto when in operative position, and supporting the leg frames in a minimum space and in compact relationship when in their folded or inoperative positions, thereby enabling the table to be transported or stored readily and to be packed conveniently for shipping.

While the invention has been described with reference to the particular structure herein dis-

closed, it is not confined to the details illustrated and this application is intended to cover such modifications or departures as may come within the purposes of the improvement or the scope of the following claims.

I claim:

1. In a table of the type including leg frames of inverted U-shape foldably secured to the bottom of the table, the improvement which consists in depending flanges secured to the bottom of the table, lateral strips secured to the bottom of the table and extending perpendicularly to said flanges, the top portions of the leg frames being positionable adjacent to said strips, and spring locking devices carried by said lateral strips and releasably engageable with the top portions of the leg frames, the leg frames when locked occupying positions with their top portions arranged adjacent to the lateral strips and with the legs inclining downwardly and outwardly with their lower ends approximately in vertical alinement with the ends of the table.

2. In a table of the type including leg frames of inverted U-shape foldably secured to the bottom of the table, the improvement which consists in depending flanges extending endwise of and secured to the bottom of the table in spaced relation to its side edges, links having their inner ends pivoted to said flanges and their outer ends pivoted to the legs of the leg frames, retaining strips secured to the bottom of the table spaced from the ends thereof and extending transversely between said longitudinal flanges, the top portions of the leg frames being positionable adjacent to said retaining strips, and spring locking devices carried by said retaining strips and releasably engageable with said top portions of the leg frames, the leg frames when locked occupying positions with their top portions arranged adjacent to the lateral strips and with the legs inclining downwardly and outwardly with their lower ends approximately in vertical alinement with the ends of the table.

3. In a table of the type including leg frames of inverted U-shape foldably secured to the bottom of the table, the improvement which consists in depending flanges extending endwise of and secured to the bottom of the table in spaced relation to its side edges, links having their inner ends pivoted to said flanges and their outer ends pivoted to the legs of the leg frames, channel strips secured to the bottom of the table spaced from the ends thereof and extending transversely between said longitudinal flanges, said channel strips including opposite spaced depending flanges and affording channels to receive the top portions of the leg frames, and releasable spring locking devices carried by flanges of said channel strips and engageable with openings in the top portions of the leg frames.

4. In a table of the type including leg frames of inverted U-shape foldably secured to the bottom of the table, the improvement which consists in depending flanges extending endwise of and secured to the bottom of the table in spaced relation to its side edges, links having their inner ends pivoted to said flanges and their outer ends pivoted to the legs of the leg frames, channel strips secured to the bottom of the table spaced from the ends thereof and extending transversely between said longitudinal flanges, said channel strips including opposite spaced depending flanges, the inner flanges being of greater height than the outer flanges, and releasable spring locking tongues carried by said

inner flanges and engageable with openings in the top portions of the leg frames when the latter are in operating position, the leg frames when locked to said inner flanges occupying positions with their upper portions arranged in the channels spaced from the ends of the table and the legs inclined downwardly with their lower ends approximately in vertical alinement with the ends of the table and when folded occupying positions in juxtaposition and conforming to the outer edge of the table and between said outer edge and said longitudinal flanges with the ends of the legs in adjacent relationship and the legs arranged in the same horizontal plane.
